UNITED STATES PATENT OFFICE.

BICKNELL HALL, OF TAUNTON, MASSACHUSETTS.

LEATHER-BURNISHING MECHANISM.

1,382,504.

Specification of Letters Patent. Patented June 21, 1921.

Application filed April 27, 1912, Serial No. 693,657. Renewed September 29, 1919. Serial No. 327,269.

To all whom it may concern:

Be it known that I, BICKNELL HALL, a citizen of the United States, and a resident of Taunton, in the county of Bristol and 5 State of Massachusetts, have invented an Improvement in Leather-Burnishing Mechanism, of which the following description, in connection with the accompanying drawings, is a specification, like characters on the 10 drawings representing like parts.

This invention relates to leather burnishing mechanism.

In order that the principle of the invention may be readily understood, I have 15 disclosed a single embodiment thereof in the accompanying drawings, wherein—

Figure 1 is a vertical, longitudinal section of leather burnishing mechanism embodying my invention;

20 Fig. 2 is a detail in vertical longitudinal section of a portion of such mechanism;

Fig. 3 is a view partially in plan and partially in horizontal section of the mechanism shown in Fig. 1;

25 Fig. 4 is a transverse section upon the line 4—4 of Fig. 3;

Fig. 5 is an enlarged detail in plan and horizontal section of a portion of the mechanism shown in Fig. 3;

30 Fig. 6 represents one of the burnisher elements in transverse section;

Fig. 7 is a plan view and Fig. 8 a vertical, transverse section of a modified form of my invention; and

35 Figs. 9 and 10 are views similar to Figs. 7 and 8 respectively of still another form of my invention.

An important object of my invention is so 40 to prepare an edge or edges of leather for use in the manufacture of boots and shoes as to obtain all the advantages as well as the appearance of a folded edge heretofore obtained by thinning one edge of the leather and folding it on itself prior to subjecting 45 the same to a burnishing action.

In accordance with my invention, I preferably provide a plurality of burnishing elements, both of which, if but two are employed, are preferably heated, and both of 50 which are preferably driven, said burnishing elements engaging the same edge of the leather, the first acting to round the edge thereof. In the event that a dressing is employed to soften the leather, the heat of the 55 first burnisher element sets the dressing, so that the edge holds its rounded shape. The

succeeding burnisher element preferably has a to and fro movement relative to the work, so as to rub the shaped edge and assist in preserving the shape thereof. 60

Referring more particularly to the drawings, the bed plate is represented at 1, it being preferably of metal and supporting in underneath bearings 2, 3, a preferably horizontal drive-shaft 4 driven in any suitable 65 manner, as, for example, by means of a pulley 5 normally loose thereon but adapted to be clutched thereto in any suitable manner. Herein for the purpose I have represented the pulley 5 as having a recessed clutching 70 face 6 to receive the frictional, conical clutching face 7 of a clutch member 8 splined upon a member fast on the shaft 4 as indicated at 9, movable axially thereof and adapted to be projected into clutching 75 relation with the pulley 5 in any suitable manner. Herein I have represented a coiled spring 10 tending constantly to force the clutch member 8 into clutching relation with the pulley 5, which is held from longitudinal 80 movement along the shaft 4 by a collar 11 fast on said shaft. An arm or member 12 engages the peripheral groove 13 of said clutching member 8 and when projected to the left, viewing Figs. 1 and 3, disengages 85 the clutch member 8 from the pulley 5 against the tension of the spring 10. I may shift the clutch operating arm or member 12 in any suitable manner, but have herein represented it as fast upon a slide rod 14 suitably mounted in the frame work of the machine and having a rounded end 15 projecting into the path of a lever 16 pivoted at 17 upon a bracket 18, shown as bolted to the bed plate. When the longer arm of the 95 lever is moved downwardly, viewing Fig. 4, the shorter arm thereof rides against the rounded end of the slide rod 14, thereby axially projecting the same to the left viewing Fig. 3 and disengaging the clutch member 8 from the pulley 5. Upon opposite movement of the lever 16, the coiled spring 10 again projects the clutch member 8 into clutching relation with the pulley 5. It will 100 be understood, however, that any suitable clutching or other means may be employed for this purpose.

I preferably provide two burnishing members, one at least and preferably both of which are heated. In the present embodiment of the invention, I have represented a rotary burnisher electrically heated and a 110

coöperating burnisher preferably similarly heated and having a to and fro and preferably a reciprocatory movement. Preferably these burnishing elements are so constructed as to be readily applied to and removed from the operating parts of the mechanism.

The bed plate 1 is provided with an opening 19, over which, upon a surrounding shoulder 20, is supported and secured a work 10 guiding plate 21 of some suitable insulating material for heat and electricity. Depending from and secured to said plate by means of screws 22 is a block 23 having therein a bearing for a vertical shaft 24 provided at 15 its lower end with a beveled gear 25 meshing with and driven by a similar gear 26 upon the drive shaft 4. The upper end of the shaft 24 is preferably of reduced diameter, as indicated at 27, and thereonto is fitted 20 cap-wise a burnishing wheel 28 preferably formed of some metal adapted to be readily heated by the application of an electric current. The wheel 28 is provided with a grooved periphery 29 to receive the edge of 25 the leather to be burnished, and as herein shown, the face of the plate 21 is recessed or countersunk as indicated at 28' for the reception of the wheel 28 so that the groove 29 of the latter may extend to the face of 30 the plate 21, thus permitting the work to be readily guided by the plate to said groove. Preferably said wheel 28 is adapted to be readily applied to and removed from the shaft 24, so that other burnishing wheels 35 may be substituted therefor. To this end, I have herein represented the upper end of the shaft 24 as transversely slotted or socketed as indicated at 30, and the said wheel is provided with a transverse pin 31 adapted 40 to be seated in said slot or socket, thereby rendering said wheel fast upon the shaft 24. Preferably the wheel 28 does not directly contact with the shaft 24, there being interposed a thimble or lining 32 of insulating 45 material for heat and electricity.

In practice, but a negligible amount at least of current or of heat would be conducted by the cross pin 31 or by the pins 43. Furthermore, such pins might readily be made of 50 insulating material for heat and electricity.

In order to heat the burnishing wheel 28, I may employ any suitable device. Preferably, however, the said burnishing wheel is electrically heated, and to that end I have 55 represented a heating coil 33 connected to any suitable source of electricity and having in its lower end a recess or socket 34 into which the projecting axial end of the wheel 28 is received as indicated in Figs. 1 and 2. 60 In order to permit the accurate positioning of the burnishing wheel with respect to the heating coil, the latter is preferably longitudinally and herein vertically adjustable. While any suitable means may be employed 65 for this purpose, I have in Fig. 1 repre-

sented the said coil as provided with an axial screw 35 passing through a supporting arm 36 and accurately adjustable with respect thereto by knurled nuts 37. The arm 36 is secured to a guide or tube 38 receiving 70 the wires 39 of the heating coil leading from any suitable source of electricity, said tube 38 being provided with a foot 39' removably supported within a socketed upright 40 supported upon the frame work of the machine. 75 By lifting the foot 39' of the tube or guide 38 from the socket 40, the entire heating device is readily separated from the burnishing mechanism.

In connection with the burnishing wheel 80 28, I preferably provide a coöperating burnisher element, here represented as a metallic plate 41, shown most clearly in Figs. 5 and 6, and having a grooved edge 42 arranged in parallelism with the peripheral 85 groove 29 of the wheel 28. The said plate substantially underlies the heating coil 33 so as to be effectively heated thereby and is preferably readily removable from its support and has imparted thereto a to and fro 90 movement and preferably a movement of reciprocation so as to act with a rubbing or finishing action upon the leather edge. To this end, the said plate 41 is provided with two pins 43 or other suitable securing means, 95 shown most clearly in Fig. 2 as depending into a block 44 supported within a recessed portion of the block 23 and having an elongated central aperture for the passage of the shaft 24, and permitting a to and fro movement of said block transversely of the axis of said shaft. The said block 44 is itself recessed for the reception of an eccentric block 45, which is in turn also recessed for the reception of an eccentric 46 fast upon 100 the shaft 24. The insole plate 21 is slotted as indicated at 47 to permit the described reciprocatory movement of the burnisher plate 41. The construction of parts is such that upon the rotation of the shaft 24 the 110 burnishing wheel 28 is continuously rotated in one direction and the burnisher plate 41 is reciprocated by the eccentric 46 through the intermediary of the blocks 44 and 45. Current being applied to the coil 33, both of 115 the burnishing elements are highly heated.

The grooves of the two burnishing elements are so located with respect to the face of the bed plate 1 that the leather or other work may be slid or guided flatwise 120 along said face directly into the grooves of the burnishing elements without necessitating the lifting of the work from the face of the bed plate. Heretofore so far as I am aware, it has been necessary, in order to impart a rounded edge to leather, to thin the edge and then fold it longitudinally upon itself and thereupon to subject said folded edge to the action of a burnishing element. My invention obviates the neces- 125 130

sity of thinning, and then folding the edge to be rounded, as I am enabled by the co-operative action of the two burnishing elements, first to impart a rounded edge to 5 the leather by the grooved face of the burnishing wheel 28 and then to set or preserve such rounded edge by the rubbing or 10 finishing action of the plate 41. Preferably I apply a dressing to the edge of the leather to soften the same, and the heated 15 burnishing wheel 28 acts to set the dressing which assists in preserving the rounded shape imparted to the leather edge by the groove of the burnishing wheel 28. The 20 to and fro or rubbing action of the grooved plate 41 completes the operation and effects the preservation of the said rounded shape 25 of the leather edge.

It will be evident that by lifting the tube 20 or guide 38 from the socket 40, the burnishing wheel 28 may be readily removed from the shaft 24 and the burnishing plate 41 may be lifted from its operative position, thus withdrawing the pins 43 from the 25 block 44.

In that form of the invention shown in 30 Figs. 1 to 6 inclusive, I have disclosed two burnishing members,—the wheel 28 and the plate 41,—the former being continuously rotated and the latter being reciprocated. Within the scope of my invention, I may 35 employ a single burnishing member, and if desired impart thereto a compound movement, such, for example, as a rotary or oscillatory movement about an axis and a to and fro or other suitable bodily movement.

In Figs. 7 and 8, I have represented a burnishing wheel 48 mounted upon a shaft 49 40 similar, it may be, in all respects to the shaft 24 shown in Fig. 1 and similarly driven. The block 50 is preferably similar to the block 23 and is provided with a bearing for said shaft 49. Upon the shaft 49 is an eccentric 51 and surrounding the latter is a block or eccentric strap 52. About the block or strap 52 is shown a recessed block 53 45 54 having portions thereof above and below said eccentric 51 and block 52, as indicated in Fig. 7. The upper portion of the block 53 54 is provided with an upstanding bearing 55 receiving therein the stem or projection 56 of the burnishing wheel 48, which latter is provided upon a portion at least 55 of its periphery with teeth 57 meshing with a rack 58 fixed upon the adjacent part of the frame.

The construction of parts is such that 60 upon rotation of the shaft 49, the eccentric 51 imparts to and fro movement to the block 52 and the latter imparts to and fro movement to the blocks 53, 54, thereby reciprocating the latter in the direction of feed of the work. The bearing 55 of the block 53, 54, is mounted in an elongated slot 59 of the

plate 21, so that not only is the burnishing wheel 48 vibrated or moved bodily to and fro along the path of the work, but in such vibration or bodily movement engagement of the teeth 57 with the rack 58 compels 70 an oscillation or a turning or rolling movement of the said burnishing wheel 48. Thus the said wheel 48 is not only reciprocated or vibrated at a rapid rate along the path of the work, but its oscillatory or rolling movement gives substantially the same effect to the work as the continuous rotary movement of the burnishing wheel 28. In this form of the invention the burnishing wheel 48 combines the functions of the burnishing wheel 28 and the burnishing plate 41 of that form of the invention shown in Figs. 1 to 6 inclusive. In connection with that form of the invention shown in Figs. 7 and 8, I provide heating means, preferably essentially the same as that shown in Figs. 1 to 6 inclusive, the heating coil 33 being 85 interiorly recessed sufficiently to permit the to and fro motion of the wheel 48 or any other suitable construction being employed 90 for the purpose.

In Figs. 9 and 10, I have shown still another form of my invention, the parts being substantially similar to those represented in Figs. 7 and 8, excepting that the burnishing 95 wheel 60 is provided with an upward prolongation grooved at 61 for the reception of a driving belt 62 connected with and driven from any suitable part of the mechanism. The belt 62 being continuously 100 driven in one direction imparts a continuous rotary movement to the burnishing wheel 60 and through the shaft 49 the said wheel is reciprocated or vibrated to and fro along the path of the work.

In this form of the invention also the burnishing wheel 60 combines the functions of the burnishing wheel 28 and the burnisher plate 41 of that form of the invention shown in Figs. 1 to 6 inclusive, it being understood that I may provide suitable heating means, preferably that shown in Figs. 1 to 6 inclusive.

Having thus described one illustrative embodiment of my invention, I desire it to be 115 understood that although specific terms are employed, they are used in a generic and descriptive sense and not for purposes of limitation, the scope of the invention being set forth in the following claims.

Claims:

1. Leather burnishing mechanism comprising, in combination, a work guiding plate, a burnishing wheel, means for supporting said wheel adjacent said plate and in such 125 position that the work will be guided by the plate to the periphery of the wheel, means for rotating the wheel, and electrical means for heating the wheel.

2. Leather burnishing mechanism comprising

ing in combination a burnisher wheel positioned and arranged to permit the edge of a piece of leather to be brought into burnishing relation thereto, means for rotating said wheel, means for electrically heating said wheel, and means whereby said leather edge may be guided into burnishing relation to said wheel.

3. Leather burnishing mechanism comprising, in combination, a shaft, rotating means therefor, a burnisher wheel mounted on said shaft and having an axial projection and an electrically heated coil into which said projection extends.

15 4. Leather burnishing mechanism comprising, in combination, an upright shaft, rotating means therefor, a cap-like burnisher wheel fitted onto the upper end thereof and heating means applied to the crown portion 20 of said wheel.

5. Leather burnishing mechanism comprising, in combination, an upright shaft, rotating means therefor, a cap-like burnisher wheel fitted onto the upper end thereof, insulating means between the wheel and shaft, and electric heating means for said burnisher wheel.

6. Leather burnishing mechanism comprising, in combination, a bed plate, an insulating plate thereon, a vertical shaft supported by said insulating plate, a cap-like burnisher wheel upon said shaft, insulation between said shaft and wheel, and electric heating means for the latter.

35 7. Leather burnishing mechanism comprising in combination, a shaft, a burnisher thereon, electric heating means for said burnisher in axial alignment with said shaft, and means for relatively axially adjusting 40 said shaft and heating means.

8. Leather burnishing mechanism comprising, in combination, a shaft, a burnisher thereon having a heat-receiving projection, an electric coil applied to said projection, 45 and means for adjusting said coil axially of the shaft.

9. Leather burnishing mechanism comprising, in combination, a plurality of burnishing elements, means differentially to impart 50 burnishing movement to said elements and means for electrically heating one at least of said elements.

10. Leather burnishing mechanism comprising, in combination, two co-operating 55 burnishers, means for rotating one of said burnishers and means for imparting to-and-fro motion only to the other thereby to impart differential movement to said burnishers.

60 11. Leather burnishing mechanism comprising, in combination, a shaft, a rotary burnisher thereon, means for heating the same, a reciprocating burnisher, and means for operating the same from said shaft.

65 12. Leather burnishing mechanism com-

prising, in combination, a shaft, a rotary burnisher and an eccentric on said shaft, heating means for said rotary burnisher, a reciprocating burnisher, and operating connections between the same and said eccentric. 70

13. Leather burnishing mechanism comprising, in combination, a bed plate, a bearing block and shaft supported thereby, a burnisher wheel upon said shaft, an eccentric upon said shaft within said bearing block, a burnisher slide, and operating connections between said slide and eccentric. 75

14. Leather burnishing mechanism comprising, in combination, a shaft, a burnisher slide, an eccentric upon said shaft, operating 80 connections between the eccentric and slide, and a co-operating rotary burnisher.

15. Leather burnishing mechanism comprising, in combination, a shaft, an eccentric thereon, a plurality of nested blocks about 85 said eccentric and a burnisher slide connected to the outermost of said blocks and positioned with its active face in substantial parallelism with said shaft.

16. Leather burnishing mechanism comprising, in combination, a supporting plate, a vertical shaft projecting therethrough, a burnisher plate having a to-and-fro motion upon the face of said plate, and operating connections between said shaft and burnisher 95 plate.

17. Leather burnishing mechanism comprising, in combination, a supporting plate, a vertical shaft projecting therethrough, a burnisher plate having a sliding movement 100 upon the face of said plate, an eccentric upon said shaft, and operating connections between said eccentric and burnisher plate.

18. Leather burnishing mechanism comprising, in combination, a supporting plate, 105 a vertical shaft projecting therethrough, an eccentric thereon, an eccentric block, a burnisher plate having a sliding movement upon the face of said plate and readily detachable connections between said block and said burnisher plate. 110

19. Leather burnishing mechanism comprising, in combination, a supporting plate, an upright shaft, a burnisher wheel upon and readily removable from said shaft, a 115 burnisher plate having a to-and-fro movement upon the face of said plate, an eccentric upon said shaft and readily detachable, and driving connections between said burnisher plate and eccentric.

20. Leather burnishing mechanism comprising, in combination, a plate constituting a work support, an upright shaft projecting through said support, a burnisher wheel upon said shaft and having a work receiving groove extending to the face of the plate, and heating means for said wheel. 120

21. Leather burnishing mechanism comprising in combination, a plate constituting a work support, an upright shaft projecting 125

through said support, a burnisher wheel thereon, a burnisher plate, and operative connections between said shaft and plate to impart to and fro movements to the latter, 5 said wheel and plate having burnishing grooves extending to the face of the plate.

22. Leather burnishing mechanism comprising in combination a plurality of burnishers in substantial alinement to engage 10 the same work edge, means to impart differential movements to said burnishers and means to heat one at least of said burnishers.

23. Leather burnishing mechanism comprising in combination two burnishers in 15 substantial alinement to operate upon the same work edge, means to impart differential movements to said burnishers and means electrically to heat both of said burnishers.

24. Leather burnishing mechanism comprising in combination, a wheel having a 20 grooved face to engage an edge of the work, means to rotate said wheel, a plate in substantial alinement therewith and having a grooved face to engage said edge of the 25 work, means to impart to and fro movement to said plate, and means to heat one of said members.

25. Leather burnishing mechanism comprising in combination a grooved wheel and 30 a grooved plate in substantial alinement to engage the same work edge, means to rotate said wheel, means to impart to and fro movement to said plate, and electrical means to heat both of said members.

35. 26. Leather burnishing mechanism comprising in combination a work guiding plate, a burnisher wheel having one face engaging said plate whereby the work is guided to said wheel, means for rotating the 40 wheel, and electrical means for heating the same.

27. Leather burnishing mechanism comprising in combination an upright shaft, rotating means therefor, a cap-like burnisher 45 wheel fitted on to the upper end thereof, and electrical means applied to the crown portion of said wheel for heating said wheel.

28. Leather burnishing mechanism comprising in combination two coöperative burnishers, means to rotate one of them, and 50 means to reciprocate the other in the plane of such rotation.

29. Leather burnishing mechanism com-

prising in combination, a shaft, a rotary burnisher mounted thereon, an eccentric 55 upon said shaft, a plurality of nested blocks about said eccentric, and a burnisher slide connected to the outermost of said blocks.

30. Leather burnishing mechanism comprising in combination, a shaft, an eccentric thereon, a plurality of nested blocks about 60 said eccentric, a burnisher slide connected to the outermost of said blocks, and heating means overlying said burnisher.

31. Leather burnishing mechanism comprising in combination, a burnisher wheel, rotating means therefor, and electrical heating means for said wheel constructed and arranged to inclose a portion thereof. 70

32. Leather burnishing mechanism comprising in combination, a burnisher wheel, rotating means therefor, and electrical heating means for said wheel overlying the latter and readily removable therefrom. 75

33. Leather burnishing mechanism comprising in combination two coöperative burnishers to act upon the edge of the work, and means to impart differential movement to said burnishers in the plane of the work. 80

34. Leather burnishing mechanism comprising in combination, an upright burnisher wheel having a free space about the periphery thereof permitting the edge of a piece of leather to be brought into burnishing relation thereto, means for rotating said wheel, and means for electrically heating the same. 85

35. Leather burnishing mechanism comprising in combination, an upright burnisher wheel having a free space about the periphery thereof permitting the edge of a piece of leather to be brought into burnishing relation thereto, means for rotating said wheel, means for electrically heating 90 said wheel, and guiding means for presenting the said leather edge to said burnishing wheel. 95

In testimony whereof, I have signed my name to this specification, in the presence of 100 two subscribing witnesses.

BICKNELL HALL.
